UNITED STATES PATENT OFFICE.

HANS JORDAN, OF KARLSHORST, GERMANY, ASSIGNOR TO GENERAL ELECTRIC COMPANY, A CORPORATION OF NEW YORK.

LOADING SYSTEM FOR TELEPHONE LINES.

Application filed March 15, 1923, Serial No. 625,369, and in Germany March 28, 1922.

In the construction of phantomed telephone lines, it is necessary to insert coils in the lines in such manner that a desired degree of inductance is effective in each of the three combined speaking circuits; that is, in the two main lines and in the phantom line. The resistance of the lines should at the same time be increased as little as possible. Further, care should be taken that, by the insertion of the coils, no disturbances of the mutually connected lines and of the adjacent lines are occasioned.

In the arrangements of coils which have mainly been employed heretofore for this purpose, by any method of operation of the lines only a small part of the windings has served the intended purpose. The other very considerable part was not only ineffective, but was even harmful by reason of the resistance of its turns.

Devices in which several windings belonging to separate circuits are combined into one coil tend toward the mutual disturbance of the mutually connected circuits. Such devices, therefore, require special precautions for preventing disturbances, and are therefore difficult and costly to make.

Among other devices known, the combining of the two duplex coils, into one coil has the disadvantage, besides that of the dead turns, of complicated equalization as regards mutual disturbances.

By certain proposed arrangements which obtain the loading of the multiplex line by magnetic concatenation of the main coils, the dead turns are avoided. But in such arrangements special precautions are required in order to obviate the mutual disturbances. This arrangement also becomes thereby complicated to produce.

The object of the present invention is to provide a loading system which will be free from these disadvantages. The self-induction coils of my invention permit not only an improvement in the properties of the conductor and a saving in material and space, but their manufacture is also much simpler, and therefore cheaper, than that of the types of coils heretofore known for the simultaneous loading of main and duplex lines.

The novel features which I believe to be characteristic of my invention are pointed out with particularity in the appended claims. My invention itself however both as to its organization and method of oper-

ation will best be understood by reference to the following description taken in connection with the accompanying drawing in which Fig. 1 shows diagrammatically the general type of telephone system to which my invention may be employed; Figs. 2 and 3 are diagrammatic representations of single coil windings illustrating the manner in which coils suitable for carrying out my invention may be constructed; and Figs. 4 and 5 are diagrammatic representations of two different forms of loading systems with which my invention may be employed.

In Fig. 1 is shown a known and frequently employed system of connections by which on each of the two main lines 1^a, 1^b and 2^a, 2^b, which serve as main circuits, two subscribers T¹, T² and T³, T⁴ communicate, and on the phantom circuit formed from the main circuits two subscribers T⁵, T⁶ communicate. The lines are equipped with, in all, four coils at each of the coil points P¹, P², etc. The coils S of the same kind serve for loading the main circuits, and the coils V of the same kind serve for loading the phantom circuit. Each coil carries two like windings, which may be wound in the same sense. The windings W¹ and W² of coils S are connected in the same direction as regards the currents in the corresponding main circuit, and the windings W³ and W⁴ of the coils V are connected in opposite directions, so that the magnetic fields created by a current in the main circuit are intensified in the coils S and are weakened in the coils V. In Fig. 1 the windings are, for the sake of clearness, shown in a manner as if each of them covered one-half of the annular iron core. In reality, each winding is distributed over the entire periphery of the ring. Then the fields of the two windings neutralize each other in the coils V if a current is created in the corresponding circuit, and so do the fields of the two windings of the coils S, if a current is produced in the phantom circuit. In both cases, however, an unnecessary resistance remains in the circuit, by reason of the ineffective turns.

The present invention makes it possible to reduce the dead resistance to a minimum without the necessity at the same time of making provisions for the equalization of alternating effects by the combination of a considerable number of windings in one coil element.

For an explanation of the invention, in accordance with which the number of these ineffective windings is reduced to a minimum, it is first assumed in Fig. 2 that the 5 windings W^1 , W^2 , W^3 and W^4 of Fig. 1 are placed on one core, and are connected in the same manner as in Fig. 1. The windings have again the same direction, and W^1 and W^3 are connected in the same direction, 10 but W^2 and W^4 are connected in series in opposite directions. Thus whether these coils are traversed by currents of the main circuit or the phantom circuit, the fields of W^2 and W^4 will always be of opposite direction. Since here also, for the sake of clearness in the drawing, the windings cover only 15 part of the ring, but in reality each of the four windings covers the entire ring, only the difference of the numbers of turns of W^2 and W^4 has any effect. With respect 20 therefore to the field actions and the resulting inductances for all systems of connection, a pair of coils S , V (Fig. 1) may be replaced by one individual coil in accordance 25 with Fig. 3. Let N_s be the total number of turns of the coil S (Fig. 1), N_v the total number of turns of the coil V (Fig. 1), and it may then be assumed according to the 30 ratios of most of the lines heretofore constructed that N_s is greater than N_v . If moreover the same cores are assumed for the coils in Fig. 1 and for the coil in Fig. 2 there will be in the coil of Fig. 2 in the a -wire

$$35 \quad \frac{N_s}{2} + \frac{N_v}{2}$$

turns, and in the b -wire

$$40 \quad \frac{N_s}{2} - \frac{N_v}{2}$$

effective turns. The entire coil of Fig. 2 therefore carries

$$45 \quad \left(\frac{N_s}{2} + \frac{N_v}{2} \right) + \left(\frac{N_s}{2} - \frac{N_v}{2} \right) = N_s$$

effective turns, that is, only as many turns as in Fig. 1 one of the two coils carries, namely, the coil S .

50 The coil of Fig. 3 is unsymmetrical with relation to the two winding portions. In order, on the one hand, to utilize the advantages of this kind of winding, but on the other hand in order to maintain the symmetry of the main lines, such coils may, according to the invention, be used on one of the two systems of connections shown in Fig. 4 and Fig. 5 in which the lines, the subscribers and the coil points are designated as in Fig. 1.

According to Fig. 4 one of the coils shown in Fig. 3 is situated in each of the two successive coil points P^1 and P^2 in each main line, but in such manner that in one conductor a winding with a large number of

turns and a winding with a small number of turns always follows each other. In using the foregoing arrangement, it is to be observed that those portions of the line between successive loading points should be 70 so designed that undesirable effects produced in the propagation of the waves through any such part of the line shall not be perceptible in that part. Under such conditions, it is sufficient if the actual balance of the line is reestablished at the successive loading points by the alternate position of the coils. Thus, at any point in such a line the currents in the two conductors are equal in amount so far as practical effects are concerned. For a calculation of the effective inductance it follows from the above that it is given, as in symmetrical coils, by the number of turns, regard being had to the direction of rotation 80 of the current.

In special cases, say in the case of short lines with a small number of coil points, if it be assumed that sufficient symmetry is not established by the arrangement of Fig. 90 4, the arrangement shown in Fig. 5 may be adopted in accordance with the invention. In Fig. 5 a phantomed line is shown in which the inductance of the coil wound in accordance with Fig. 3 for each coil point 95 (Fig. 4) is distributed between two like coils which are connected in such manner in a main line that a winding of a higher and one of a lower number of turns is connected in every conductor. In this way the 100 desired symmetry is established at each individual coil point. This arrangement also brings very substantial advantages over the connections of Fig. 1, although four coils are used for each coil point.

105 It will be obvious at once from a consideration of Figs. 2 and 3 and the discussion above given that there is a large reduction in the number of turns of wire in loading coils necessary at any given loading point and that there is accordingly a large reduction in the dead resistance of the circuit. Where it is possible to use the coils in the arrangement shown in Fig. 4 the reduction 110 in the number of turns and in the total resistance is, of course, larger than in the arrangement shown in Fig. 5, but even with the arrangement of Fig. 5 the decrease in the number of turns in the loading coils represented at any loading point is obvious. 115 The saving in coils amounts to from 30% to 50%, depending on the character and condition of the lines.

120 With a reduction of the number of turns, the size of the coils will generally be reduced also, and thereby material and space will be saved without greatly impairing the properties of the coils. If there is no necessity for reducing the resistances resulting 125 from the arrangement according to Fig. 1, 130

then further very great savings in material and space will be obtained. In addition to the above mentioned advantages it may be pointed out that with this invention only 5 one type of coil is ever used or one kind of conductor wire, and each coil carries at most two windings, one with a greater and one with a smaller number of turns.

It is known that the coils, even when made 10 very carefully as regards observing the proportions of the core and the numbers of turns, do not at first prove as uniform as must be required with a view to the character 15 of the conductor wire. On the contrary, repeated measurements are necessary for equalizing the inductances by winding or unwinding turns. This results in a considerable 20 number of working processes, the number of which operations increases with the number of the windings, so that multiple coils involve special requirements in this respect. That the equalization is still more difficult as regards mutual disturbances, has 25 already been stated. Also in the case of coils according to Fig. 1, the individual windings have often been divided up and thereby the number of equalizing operations have been further increased. The coils according 30 to the invention have only one winding with a large number of turns, in which small variations, say, in the proportions and the properties of the cores may exert a great influence on the inductances to be attained. The same per cent of faults in the small 35 supplementary winding has however a correspondingly smaller influence on the total result. Thus only the winding having large numbers of turns will require equalization, and there is no reason for dividing this 40 winding. Moreover the supplementary winding may be placed over the main winding, and the capacity between the two windings may be reduced in a manner already known in itself by means of suitable intermediate layers, since thereby, with the small 45 number of turns, the total length of wire will be only slightly increased.

What I claim as new and desire to secure

by Letters Patent of the United States, is,—

1. A loading system for phantomed telephone lines comprising coils, each of which has two windings of unequal number of turns, the sum of the number of turns in the two windings being such as to give the desired inductance for the main circuit when the two coils are connected in opposite sides thereof and act in the same sense, and the difference in the number of turns of the two windings being such as to give the desired inductance for one side of the phantom circuit when the two coils are acting in opposite senses in the two conductors constituting one side of the phantom circuit. 55

2. A loading system for phantomed telephone lines comprising coils, each of which has two windings with a different number of turns, the numbers of turns of the two windings being so proportioned that the number of turns which in the operation of the line contribute only to the resistance of the line without supplying inductance thereto is reduced to the minimum, at least one such coil being connected with a separate winding in each side of the main line at each coil point and the successive coils being so 75 connected in the line that windings having the greater and smaller number of turns follow each other alternately. 65

3. A loading system for phantomed telephone lines comprising coils, each of which has two windings with a different number of turns, the numbers of turns of the two windings being so proportioned that the number of turns which in the operation of the line contribute only to the resistance of the line without supplying inductance thereto is reduced to the minimum, two such coils being connected in series, with a separate winding in each side of the main line at each coil point, a winding having the larger 90 number of turns being connected in series with a winding of the smaller number of turns. 80

In witness whereof, I have hereunto set my hand this 15th day of February, 1923.

HANS JORDAN.
